UNITED STATES PATENT OFFICE.

FRANK WILLIAM BACON, OF LOS ANGELES, CALIFORNIA.

TARIFF-BOOK.

1,074,684.

Specification of Letters Patent.

Patented Oct. 7, 1913.

Application filed July 25, 1912. Serial No. 711,568.

To all whom it may concern:

Be it known that I, FRANK W. BACON, a citizen of the United States, residing at Los Angeles, in the county of Los Angeles and 5 State of California, have invented a new and useful Tariff-Book, of which the following is a specification.

This invention relates to a book designed for use by railroad conductors and other officials or persons who require to ascertain the fare and distance between stations along the line, and the main object of the invention is to provide a book so constructed that by proper manipulation such that by simply 10 opening the book, the fare and distance between any two places may be immediately seen.

Heretofore, so far as I am aware, the only methods for obtaining distances and fares 15 between stations, is by means of tables and the tracing out of the stations and properly locating the distances relating thereto, was very difficult and mistakes were easily made, all of which is avoided by the present invention.

The device while especially adapted for railroad officials, may also be used to advantage in any situation where it is desired to ascertain quickly the distance between places 20 on a route, or the rate for any place on a route or circuit.

Referring to the drawings: Figure 1 is a front elevation, showing the book open and about to be used. Fig. 2 is a view similar to 25 Fig. 1, showing the leaves turned to give the distance. Fig. 3 is an enlarged section on line x^3-x^3 , Fig. 1. Fig. 4 is a plan view of a portion of a leaf in detail. Fig. 5 is a view similar to Fig. 4, of another leaf. Fig. 30 6 is a view similar to Fig. 4, of another leaf. Fig. 7 is a plan view of a portion of a leaf on the lower half of the book. Fig. 8 is a view similar to Fig. 7, of another similar leaf. Fig. 9 is a view similar to Fig. 7, of another similar leaf. Fig. 10, is a plan view 35 of the central portion of the book, showing portions of both upper and lower leaves and illustrating a branch road.

The book is preferably of pocket size, as 40 indicated and consists of two covers 1 and 2, united by suitable means 3, and filled with a set of upper leaves 4 and lower leaves 5. I refer to the leaves in this manner as it will 45 facilitate the description. The leaves are fastened in the book in any desired manner.

It is not essential that the leaves be permanently fastened in the book, but for the use of conductors, I prefer that the leaves be fastened in the book in the manner indicated, as they are then not easily lost out as 60 would be the case if they were loose cards, and their order of arrangement is also positively maintained.

Opening the book at the middle, all of the stations along a given division of the 65 road are displayed in consecutive order to the view. Thus, for example, as shown, the stations seen are those on a division of the Southern Pacific Railroad from Los Angeles to Yuma. The stations are arranged in the 70 order which they occupy on the division, "Los Angeles" being on the first line at the top of the upper pages, and "Yuma" being located on one of the lower pages. The first upper leaf 6 is printed with the first station, 75 viz., "Los Angeles." The next upper leaf 7 is printed with the name of the next station on the division, viz., "Dolgeville." The third upper leaf 8 is printed with the third station on the division, viz., "Alhambra," 80 and so on, continuing through the upper leaves, including the station "Durbrow" which is located on the last of the upper leaves 9. The station "Meca" is printed on the first sheet 10^a of the lower leaves and 85 the remaining stations of the division are printed on the subsequent lower leaves. The first leaf 6 is cut away below the name "Los Angeles," so that only the left portion thereof remains. The second sheet 7 is cut 90 away below the name "Dolgeville" so that only the left half of that sheet remains, and the third sheet 8 is also cut away below the name "Alhambra," so that all the left portion of that sheet remains, and the remain- 95 der of the upper sheets are similarly cut away until the last sheet 9 which contains the station "Durbrow" which is the last one on the upper leaves and need not be cut away, for there are no more stations beneath it 100 to be seen on the upper leaves. This manner of cutting away the sheets, reveals the names of all of the stations at a glance, each station having a separate leaf. Referring to the lower sheets, the first sheet 10 containing the station "Meca" is cut away below the word "Meca" and the subsequent sheets are cut away in the same manner, similar to the upper sheets 4. The two sheets 6 and 10^a constitute virtually a single 110

sheet when the book is opened out, the sheets 7 and 11 which lie next under sheets 6 and 10^a also constitute virtually a single sheet when opened out, and so do sheets 8 and 12 in like manner, and the remaining sheets are arranged in the same way. The first sheet 6 containing the station "Los Angeles" at the top is ruled off with horizontal lines 13 which form horizontal columns designated 14, which aline with the respective stations. Thus column 14 alines with "Los Angeles," column 14^a alines with "Dolgeville," column 14^b alines with "Alhambra," column 14^c alines with "San Gabriel," and so on. Column 14^d which is formed on the lower leaf 10 alines with "Meca" and so on. The sheets 6 and 10 and subsequent pairs of sheets are also ruled with vertical lines 15 which form a series of vertical columns 16, 17, 18, 19 and 20. The particular arrangement in these columns may be varied, but I prefer to place in the column 16, the fare, in the column 17, "changed fare," in column 18, "half fare" in column 19, the miles from the top station to the bottom station, and in column 20, the miles from the bottom station to the top station. At the right of each station name is a column 21 which contains the station number. Thus taking "Los Angeles," its station number in column 21 is "484," the fare is "0" the half fare is "0," the miles from "Los Angeles" is of course "0," while the miles from Yuma in column 20 is "252." Still following Fig. 1, the station "Frink" is numbered "656" as given in column 21, the fare from Los Angeles is "\$6.15," the half fare is "\$3.08," the miles from "Los Angeles" is "174" and the miles from "Yuma" is "78."

Now, let it be assumed that a person gets on the train at "Colton" and tells the conductor that he desires to pay his fare to "Iris." The conductor first opens the book at the middle so that it opens as shown in Fig. 1. He then places his thumb, as indicated, on the sheet containing the name of the station from which the fare is to be paid, and then with a movement of the hand still grasping the book, flips the book so that all of the upper leaves 4 which lie above the sheet containing "Colton" fly over and fall upon the bottom portion of the book. In the present instance ten sheets are thus flipped over to the bottom of the book, which sheets respectively contain the names of stations as follows: "Ontario," "Pomona," "Lemon," "Puente," "Bassett," "Monte," "San Gabriel," "Alhambra," "Dolgeville" and "Los Angeles." The book then shows as in Fig. 2, and the only operation required to produce this, being to simply place the thumb on the station from which the fare is to be paid and flip the overlying pages down onto the bottom part of the book. This having been done, the conductor glances

down the list of stations until his eye reaches the name "Iris" which is the name of the station to which the passenger stated he wished to pay his fare. The conductor glances at column 16 and immediately notices that the fare is "\$5.15." This operation requires obviously less than a second's time, and its advantage over the old method of tracing out long lines of numbers and intersecting columns is apparent. Now, with the book in the position shown in Fig. 2, attention is called to the fact that on the reverse side of the uppermost leaf 4 as turned over, is printed the names of the stations which would otherwise be visible immediately below the right-hand portion of that leaf. Thus that leaf which I have designated 21, on its obverse side contains the station "Ontario" and the right-hand portion of the leaf when flipped over onto the lower part of the book, would obscure several stations, viz., "Ruthven," "Drylyn," "Cactus," "Ogilby," "Knob," "Hanlon Jct." and "Yuma," and therefore, those stations have been printed on the reverse side of said sheet 21, so that when that sheet is flipped over, those seven stations appear to the view. In each instance each upper leaf has printed on the reverse side of its right-hand portion, the names of all of the stations which would be visible at such points when the sheet is turned over onto the bottom part of the book. The upper sheets are not printed with anything above the name of the station for which they stand, thus, the sheet containing the station "Colton" is not printed with any station above that station because that portion of the sheet is not used, but the reverse side of this part of the sheet would be printed with the names of stations from "699" to "733."

I provide a blank column 17, in which the conductor may write the corrected or changed fare for any station. Thus if the railroad changes the fare from a given point to a certain station, it is possible to correct the fare in the book without disfiguring the book, for example, suppose the fare from "Los Angeles" to "Pomona" has been changed from "\$.99" to ".95." The conductor simply crosses out in column 16, the figure ".99" and writes the figure ".95" in column 17, as indicated in Fig. 1. I have also indicated how the fare from "Los Angeles" to "Monte" may be changed from "\$.39" to ".35." The use of the half fare column is obvious. If the person paying the fare is to pay a half fare, the conductor ascertains the half fare from column 18 instead of reading full fare from column 16 and in the example before given, the half fare from "Colton" to "Iris" would be "\$2.58." If it be desired to know the mileage from any given station to either terminal of the division, it can be ascertained

from columns 19 or 20. Thus if it be desired to know the mileage from "Colton" to "Iris," column 19 shows the mileage to be "133." If it be desired to know the mileage 5 from "Iris" to "Yuma," column 20 gives the mileage as "59," this being found from the book as opened for "Colton" as in Fig. 2. If it be desired to ascertain the distance 10 from "Los Angeles" to any point on the division, or from "Los Angeles" to "Yuma," the book will be open as in Fig. 1, and the miles will be found in columns 19 or 20, opposite the name of the station. No 15 mental computation is necessary in any of the foregoing.

Assume that it is desired to ascertain the fare from "Acolita" to "Knob." The conductor will first open the book as shown in Fig. 1, to reveal all of the stations. He will 20 then place his thumb on the sheet containing the number "691" which is the sheet containing the station "Acolita" and will then give the book a slight jerk which will flip all of the lower sheets which lie above the 25 sheet containing "Acolita" onto the upper part of the book, an operation the reverse of that in the previous example given, and when the leaves have thus been flipped over, he will see at a glance, the fare from "Acolita" to "Knob," the amount of fare being 30 given in column 16 opposite the word "Knob." The drawings do not show this example, but it will be readily understood.

Figs. 4, 5 and 6 show the detail construction of the three uppermost leaves 6, 7 and 8. Fig. 7 shows the detail construction of leaf 10 which lies immediately above leaf 10^a and is the companion leaf to leaf 6 for "Los Angeles." Fig. 8 shows the detail of 40 the sheet containing "Meca" and Fig. 9 shows the detail sheet containing "Kaleb." Fig. 10 is a view similar to Fig. 1, but broken away at top and bottom and illustrates a branch road which extends from 45 "Calexico" to "Imperial Jct." This branch of the division is always obtained by placing the thumb on the sheet containing "Imperial Jct.," "668," and then flipping the leaves open to bring the stations as in Fig. 50 10, by which fares and distances are readily seen.

What I claim is:

1. A tariff book comprising a plurality of leaves, the leaves being in two sets on opposite sides of the hinge line of the book, the leaves of each set having horizontal columns bearing indications of the amounts of fare from a station to other stations, said leaves of both sets being cut away on 55 the same side to form alined marginal stepped tab portions bearing on obverse and reverse faces the names of the stations, the stepped marginal tab portions of the two leaves presented to view on each side of the 60 hinge line when the book is opened at any 65

point descending in the same direction and presenting the names of the stations in consecutive order.

2. A tariff book comprising a plurality of leaves, the leaves being in two sets on opposite sides of the hinge line of the book, the leaves of each set having horizontal columns bearing indications of the amounts of fare from a station to other stations, said leaves of both sets being cut away on the same side to form alined marginal stepped tab portions bearing on obverse and reverse faces the names of the stations, the stepped marginal tab portions of the two leaves presented to view on each side of the hinge line when the book is opened at any point descending in the same direction and presenting the names of the stations in consecutive order, 70 the reverse face of those leaves which lie intermediate the terminal stations bearing the names of stations concealed by a leaf of a set when that leaf is folded on top of the other leaf of that set. 75

3. A tariff book comprising a plurality of leaves, the leaves being in two sets on opposite sides of the hinge line of the book, the leaves of each set having horizontal columns bearing indications of the amounts of fare from one station to other stations, said leaves of both sets being cut away on the same side to form alined marginal stepped tab portions bearing on obverse and reverse faces the names of the stations, the stepped marginal tab portions of the two leaves presented to view on each side of the hinge line when the book is opened at any point descending in the same direction and presenting the names of the stations in consecutive order, 90 the said names of stations being arranged in line with the respective horizontal columns containing designations of fare, said leaves also having vertical columns with designations of the miles between the respective stations and terminal, each of said mileage designations being located 95 in a horizontal column in line with the name of the station corresponding to that mileage from the terminal station. 100

4. A tariff book hinged in the middle and containing a plurality of leaves, the leaves being cut away on the same side to form alined marginal stepped tab portions, said tab portions bearing on obverse and reverse faces the names of stations, said names being arranged parallel to the hinge line of the book, the leaves of the book when opened presenting to view a continuous line of the station names, the said line of names extending uninterruptedly across the hinge line of the book. 105

5. A tariff book hinged in the middle and containing a plurality of leaves, the leaves being cut away on the same side to form alined marginal stepped tab portions, said tab portions bearing on obverse and reverse 115 120 125 130

faces the names of stations, said names being arranged parallel to the hinge line of the book, the leaves of the book when opened presenting to view a continuous line of 5 the station names, the said line of names extending uninterruptedly across the hinge line of the book, the leaves being provided with horizontal columns extending parallel to the hinge line of the book, one of 10 said columns being in line with the name of the station on that leaf, the other horizontal columns on that leaf being in line with respective names of stations on other leaves, each leaf also containing vertical 15 columns at right angles to the hinge line of the book, a vertical column containing indications of fares in line with the respective horizontal columns and with the other stations alined therewith.

20 6. A tariff book hinged in the middle and containing a plurality of leaves, the leaves being cut away on the same side to form alined marginal stepped tab portions, said tab portions bearing on obverse and reverse 25 faces the names of stations, said names being arranged parallel to the hinge line of the book, the leaves of the book when opened presenting to view a continuous line of the station names, the said line of names ex- 30 tending uninterruptedly across the hinge line of the book, the leaves being provided with horizontal columns extending parallel to the hinge line of the book, one of said columns being in line with the name of the 35 station on that leaf, the other horizontal columns on that leaf being in line with respective names of stations on other leaves, each leaf also containing vertical columns at right angles to the hinge line of 40 the book, a vertical column containing indications of fares in line with the respective horizontal columns and with the other stations alined therewith, a vertical column 45 also being blank in which may be written a changed fare.

7. A tariff book comprising a plurality of

leaves, the leaves being in two sets on opposite sides of the hinge line of the book, the leaves of each set having horizontal columns bearing indications of the amounts 50 of fare from that station to other stations, said leaves being cut away on the same side to form alined marginal stepped tab portions bearing on obverse and reverse faces the names of the stations, the stepped 55 marginal tab portions of the two leaves presented to view on each side of the hinge line when the book is opened at any point descending in the same direction and presenting the names of the stations in 60 consecutive order, a leaf in said book having on it in consecutive order the names of stations on a branch of the division, one of said branch names being the junction point which appears to view as one of the 65 regular stations of the division, the other names of said branch stations being concealed by the other leaves of the book.

8. A tariff book hinged in the middle and containing a plurality of leaves, the leaves 70 being cut away on the same side to form alined marginal stepped tab portions, said tab portions bearing on obverse and reverse faces the names of stations, said names being arranged parallel to the hinge line of 75 the book, the leaves of the book when opened presenting to view a continuous line of the station names, the said line of names extending uninterruptedly across the hinge line of the book, each leaf having a vertical 80 column containing designations of distances of respective stations from one terminal and another vertical column containing designations of distances between respective stations and the other terminal. 85

In testimony whereof, I have hereunto set my hand at Los Angeles, California, this 19th day of July, 1912.

FRANK WILLIAM BACON.
